UNITED STATES PATENT OFFICE.

JOHN O. McKEAN, OF WESTFIELD, MASSACHUSETTS, ASSIGNOR TO FOSTER MACHINE COMPANY, OF WESTFIELD, MASSACHUSETTS, A CORPORATION OF MASSACHUSETTS.

YARN-COMPENSATING DEVICE FOR CREELS.

Application filed November 11, 1925. Serial No. 68,367.

It has been practically impossible to keep yarn from kinking as it passes from the yarn supply to the warping machine. This is especially true when the warping machine 5 stops and the yarn is at rest.

The object of my invention is to provide a novel compensating device tending to keep the kinks out of the yarn either while the yarn is running or when it is at rest by maintaining the yarn taut to a certain extent at 10 all times.

My invention more particularly includes a creel having a series of fixedly mounted vertical rods around each of which rods the 15 yarns from one or more rows of cops are wound as they pass from their cops, said vertical rods allowing the yarns to drop by gravity on said rods to automatically take up slack in the yarns when their travel is 20 stopped.

A practical embodiment of my invention is represented in the accompanying drawings, in which—

Fig. 1 represents a detail side view of a 25 creel with my yarn compensating devices included therein.

Fig. 2 represents a section taken in the plane of the line II—II of Fig. 1, looking in the direction of the arrows.

Fig. 3 represents a detail side view on an 30 enlarged scale showing a cop, its tension device and the vertically disposed rod which forms the yarn compensating device.

Fig. 4 represents a detail horizontal section taken in the plane of the line IV—IV of 35 Fig. 3, looking in the direction of the arrows.

The creel frame is denoted by 1. The cops 2 are arranged in a plurality of vertical rows, the holders 3 for the cops of each vertical 40 row being carried by a vertically disposed supporting bar 4 pivoted in the creel frame 1, to rock on a vertical axis to swing the cops to and from their doffing position.

In proximity to each vertical supporting 45 bar 4 I mount a vertically disposed rod 5 in the creel frame 1, around which rod the yarns

are wound as they pass from their cops to the warping machine (not shown herein).

The rod 5 which acts as the yarn compensating device is provided with a vertical row 50 of brackets 6, each of which carries a tension device 7 of any well known or approved construction, through which tension device the 55 yarn passes after it leaves the bar 5. I have found that by winding the yarn around the bar 5 on its way from the cop to the tension device, the bar operates to keep the yarn comparatively taut whether the yarn is or is not running, thereby tending to take the kinks 60 out of the yarn when the yarn is running and also to keep the yarn from kinking when it is at rest. Furthermore, the tension device through which the yarn passes also tends to 65 take those kinks out of the yarn which have not already been taken out by the compensating device.

What I claim is:

1. A yarn supply, a yarn tension device located below the yarn supply and a vertically disposed rod around which the yarn is 70 wrapped at least once as it passes from the yarn supply to the tension device, said rod operating to keep the yarn comparatively 75 taut when the yarn is running and at rest, thereby tending to take out the kinks when running and to keep the yarn from kinking when at rest.

2. A plurality of yarn supplies, a plurality of yarn tension devices located below their respective yarn supplies and a vertically disposed rod around which the yarns are wrapped at least once as they pass from the 80 yarn supplies to their respective tension devices, said rod operating to keep the yarns comparatively 85 taut when the yarns are running and at rest, thereby tending to take out the kinks when running and to keep the yarns from kinking when at rest.

In testimony, that I claim the foregoing as my invention, I have signed my name this 9th day of Nov. 1925.

JOHN O. McKEAN.
